United States Patent Office

Des. 185,653
Patented July 7, 1959

185,653

ASH TRAY

Charles A. Woods, Burbank, Calif.

Application May 19, 1958, Serial No. 50,982

Term of patent 14 years

(Cl. D85—2)

FIG. 1.

FIG. 2.

Des. 185,653

PAGE 2

FIG. 3.

FIG. 4.

Fig. 1 is a perspective view of an ash tray in open position showing my new design;

Fig. 2 is a plan view thereof;

Fig. 3 is a perspective view with the ash tray in closed position; and

Fig. 4 is a bottom view thereof.

I claim:
The ornamental design for an ash tray, as shown.
